Patented Sept. 4, 1900.

S. D. POOLE.

DISK BEARING.

(Application filed June 12, 1900.)

(No Model.)

UNITED STATES PATENT OFFICE.

STALEY D. POOLE, OF MOLINE, ILLINOIS, ASSIGNOR TO THE DEERE & COMPANY, OF SAME PLACE.

DISK-BEARING.

SPECIFICATION forming part of Letters Patent No. 657,204, dated September 4, 1900.

Application filed June 12, 1900. Serial No. 20,049. (No model.)

To all whom it may concern:

Be it known that I, STALEY D. POOLE, a citizen of the United States, residing at Moline, in the county of Rock Island and State 5 of Illinois, have invented certain new and useful Improvements in Disk-Bearings; and I do hereby declare the following to be a full, clear, and exact description of the invention, such as will enable others skilled in the art 10 to which it appertains to make and use the same.

This invention relates to disk-bearings, and more particularly to bearings for disk plows and the like.

15 The primary object of the invention is to provide an efficient antifriction-bearing for a rotary cutting-disk with capacity for adjustment to permit the wearing-surfaces of the bearing to be shifted or adjusted so that the positions of such of the antifriction devices and the wearing-surfaces in contact therewith as are most liable to wear in use may be shifted or changed from time to time to obtain a new or less-worn surface, while the excessively-worn 25 surfaces are brought into positions for less wear, whereby such surfaces will be caused to wear more evenly than in devices of this same general character as heretofore constructed, thus reducing the friction and increasing the durability of the device.

30 A further object is to provide a roller and ball-bearing combined in such manner that the bottom side thrust of the disk, which is usually much the greatest, may be borne by the lower rollers, while the upward thrust is borne by the lower balls and the "pull-off" or discharge by a portion of the upper balls in the same race.

35 A further object is to provide an improved 40 compound antifriction-bearing with simple and efficient means for attaching the device to the plow standard or hanger with capacity for easily removing the same without removing or disarranging the balls or rollers in their 45 respective races.

The invention will first be hereinafter more particularly described with reference to the accompanying drawings, which form a part of this specification, and then pointed out in 50 the claims at the end of the description.

In the drawings, in which similar letters of

reference are used to denote corresponding parts in different views, Figure 1 represents a vertical sectional elevation of an antifriction disk-bearing embodying my invention. Fig. 55 2 is a detail view of the adjustable antifriction bearing-disk or race-plate; Fig. 3, a detail plan view of a broken-away portion of the roller spacing-ring, and Figs. 4 and 5 detail sectional views of modifications. 60

Referring to the drawings, the letter A may denote an ordinary concavo-convex disk, such as commonly used in the class of agricultural implements to which this invention relates, said disk having secured thereto by any suitable means, as the nuts and bolts *a a*, an annular angle-plate B, from the upper or outer edge of which a ring-flange or lugs *b b* may extend, having apertures therein to receive the fastening-bolts *a*, while the other edge of 70 said angle-plate is formed or provided with an oppositely-extending ring-flange or annulus *b'*, so as to provide an annular space or recess between the latter flange and the back of the disk to receive and confine in rotative 75 engagement therewith the peripheral portion of a race-plate or bearing-disk C, on which the cutting-disk has its bearings. The disk C is provided on its front face, at or near its circumferential portion, with a suitable annular raceway or depression of such shape as to form a bearing-surface for a series of 80 conical rollers D D, which are interposed between the said bearing-surface or raceway and the back or convex surface of the disk, said rollers 85 being preferably loosely confined at predetermined distances apart and held in fixed positions relatively to the line of rotation by suitable spacing and retaining devices—such, for instance, as the spacing-ring E, having 90 suitable apertures therein at intervals to receive the correspondingly-shaped rollers and hold them in their proper places in the race. However, rollers and retainers of any suitable form may be employed. The bearing 95 plate or disk C has an annular concave recess or depression *c* in its periphery to provide a ball-race for a series of balls located and confined therein by contact with the confronting concave surface of the interior of the annulus 100 B, at the junction of the main body portion thereof with the right-angled flange or ring

portion *b* thereon. The balls *F* are also preferably held at suitable distances apart within the ball-race by means of a spacing-ring *G*, having apertures therein to receive the balls 5 after the manner of the spacing-ring *E*, hereinbefore described, said spacing-ring *G* being arranged so as to span the space within the ball-race at such an angle to the diametrically-opposite points of contact of the balls with 10 the concave portions of the disk *C* and annulus *B* as to prevent frictional contact of the spacing-ring with the wearing-surfaces of the ball-race. In order to secure the bearing-disk *C* in proper position upon its supporting 15 hanger or standard and at the same time to provide for the adjustment thereof, so as to obtain a new wearing-surface of the antifriction devices and their races when any portion thereof has been excessively worn, the disk- 20 supporting standard or hanger, which is denoted by the letter *I*, may be provided with a series of recesses *i*, adapted to engage a lug or corresponding series of lugs *C'* upon the bearing-disk *C*, or vice versa, whereby when 25 it is desired to shift the position of the wearing-surfaces the nut *h* on the protruding end of the fastening-bolt *H* may be unscrewed and the bearing-disk *C* rotated sufficiently to bring the interlocking lug or lugs and recesses 30 into engagement, and thereupon by tightening the nut on the fastening-bolt the bearing-disk may be again secured in a fixed position relatively to the disk rotatively mounted thereon with new wearing-surfaces in the position exposed to excessive wear. 35

It will be understood, of course, that any desired number of interlocking lugs and recesses may be provided and that instead of recesses in the standard or other support for 40 the disk such support may be provided with a lug or lugs or projections for engagement with recesses in the back of the bearing-disk. It will also be understood that other suitable means may be employed for separating the 45 balls and rollers and holding them in the desired positions in their respective races and that the spacing-rings may be dispensed with, if desired; but they are preferably employed for greater efficiency, as they tend not only 50 to reduce the friction, but to increase the durability of the device and reduce the expense by rendering a less number of balls and rollers necessary. Other changes may also be made in the details of construction and arrangement of parts without departing from the spirit and scope of my invention, and hence I do not desire to be limited to the exact construction and arrangement shown and described. 55

60 By arranging the spacing-ring *G* so that it may extend diagonally across the opening or ball-race provided between the confronting annular concave surfaces on the interior of the angle-plate *B* and the inner edge or peripheral portion of the bearing-disk *C* it will 65 be sustained in proper position for separating the balls by contact of its opposite edges with

the adjacent surfaces of the angle-plate or bearing-disk, so as to prevent it from dropping down and releasing the balls, and hence 70 a plain flat ring may be used; but the spacing-ring *E*, which may bear at one side against the peripheral portion of the disk *C*, is preferably provided on the opposite side thereof with protuberances *e*, abutting the surface of 75 the bearing-plate or back of the disk confronting said protuberances, so as to hold the spacing-ring in a relatively-fixed position with reference to the rollers or other antifriction devices or in alignment with the centers thereof, and thus prevent the spacing-ring from moving sidewise, either out or in, sufficiently to release the rollers. Such raised portions may consist of a protuberance *e*, stamped or otherwise formed therein, or an upturned part 80 *e'*, as shown in Fig. 4, which may be cut or stamped out of the body of the ring, or any other suitable projections or protuberances may be used.

In Fig. 5 I have shown a detail sectional view of a modification of the bearing which is exactly similar to the construction shown in Fig. 1, except that in this construction a bearing-plate (lettered *A'* in the drawings) is employed. This plate may be in the form of 90 a flat ring or annulus, as shown, secured to the angle-plate *B*, between the latter and the back of the disk *A'*, to provide a bearing-surface confronting the annular bearing-surface on the front face of the bearing-disk *C*, and 95 it is designed to serve the double function of providing a movable wearing-surface or race-way for the rollers or other antifriction devices adapted to be easily removed and replaced when worn and to prevent the rollers 100 from falling out when the disk is removed from the bearing. This bearing-plate may be formed integrally with the angle-plate *B*; but it is preferably formed separately therefrom and bolted or otherwise secured thereto. 110 Any suitable material adapted to provide a sufficiently-hard wearing-surface may be used; but I preferably employ a plain metal ring shaped to conform to the convex surface of the disk and present on its opposite side 115 a bearing-surface adapted to conform to the shape of the antifriction devices bearing thereon.

Having thus fully described my invention, what I claim as new, and desire to secure by 120 Letters Patent of the United States, is—

1. In a disk plow, the combination with a relatively-fixed part or support and a disk rotatably secured thereto, of a series of antifriction devices interposed between the back 125 of the disk and a confronting bearing-surface on said support, and a series of antifriction devices interposed between confronting bearing-surfaces on the opposite side of said support and a rotary element carried by 130 or revolving with the disk, substantially as described.
2. In a disk plow, a composite antifriction-bearing for the disk, comprising a relatively-

- fixed part or support about which the disk may rotate, an annular series of rollers interposed between confronting bearing-surfaces on said support and the disk and an annular series of balls interposed between confronting bearing-surfaces on the opposite side of said support and a rotary element carried by or revolving with the disk, substantially as described.
- 5 3. In a disk plow, a composite antifriction-bearing for the rotary disk, comprising a relatively-fixed part or support about which the disk may rotate, an annular series of antifriction devices interposed between the back of the disk and a confronting bearing-surface on said support, and an annular series of antifriction devices interposed between confronting bearing-surfaces on the opposite side of said support and a rotary element carried by or revolving with the disk, together with means for adjusting and securing said fixed part or support so as to shift the positions of the bearing-surfaces thereon and of the antifriction devices in such manner as to cause those parts that are least exposed to wear to take the position of excessively-worn portions, substantially as described.
- 10 4. In a disk plow, a composite antifriction-bearing for the rotary disk, comprising a relatively-fixed part or support about which the disk may rotate, an annular series of conical rollers interposed between confronting bearing-surfaces on said support and the back of the disk, and an annular series of balls interposed between confronting bearing-surfaces on the opposite side of said support and a rotary element carried by or revolving with the disk, together with means for adjusting and securing said fixed part or support so as to shift the positions of the bearing-surfaces thereon and of the antifriction devices in such manner as to cause those parts that are least exposed to wear to take the position of excessively-worn portions, substantially as described.
- 15 5. In a disk plow, the combination with a relatively-fixed part or support and a disk rotatably secured thereto, of a series of antifriction devices interposed between the back of the disk and a confronting bearing-surface on said support, and a series of antifriction devices interposed between confronting bearing-surfaces on the opposite side of said support and a rotary element carried by or revolving with the disk, and means for holding said antifriction devices at suitable distances apart in their respective courses or races, substantially as described.
- 20 6. In a disk plow, a composite antifriction-bearing for the disk, comprising a relatively-fixed part or support about which the disk may rotate, an annular series of rollers interposed between confronting bearing-surfaces on the opposite side of said support and a rotary element carried by or revolving with the disk, and means for holding said antifriction devices at suitable distances apart in their respective courses or races, together with means for adjusting and securing said fixed part or support so as to shift the positions of the bearing-surfaces thereon and of the antifriction devices in such manner as to cause those parts that are least exposed to wear to take the position of excessively-worn portions, substantially as described.
- 25 7. In a disk plow, a composite antifriction-bearing for the rotary disk, comprising a relatively-fixed part or support about which the disk may rotate, an annular series of antifriction devices interposed between the back of the disk and a confronting bearing-surface on said support, an annular series of antifriction devices interposed between confronting bearing-surfaces on the opposite side of said support and a rotary element carried by or revolving with the disk, and means for holding said antifriction devices at suitable distances apart in their respective courses or races, together with means for adjusting and securing said fixed part or support so as to shift the positions of the bearing-surfaces thereon and of the antifriction devices in such manner as to cause those parts that are least exposed to wear to take the position of excessively-worn portions, substantially as described.
- 30 8. In a disk plow, a composite antifriction-bearing for the disk, comprising a relatively-fixed part or support about which the disk may rotate, an annular series of rollers interposed between confronting bearing-surfaces on said support and the disk, and an annular series of balls interposed between confronting bearing-surfaces on the opposite side of said support and a rotary element carried by or revolving with the disk, together with spacing-rings apertured at intervals to receive and hold said rollers and balls at prescribed distances apart in their respective courses or races, substantially as described.
- 35 9. In a disk plow, a composite antifriction-bearing for the disk, comprising a relatively-fixed part or support about which the disk may rotate, an annular series of rollers interposed between confronting bearing-surfaces on the opposite side of said support and a rotary element carried by or revolving with the disk, together with spacing-rings apertured at intervals to receive and hold said rollers and balls at prescribed distances apart in their respective courses or races, and means for changing the position of said support so as to cause the bearing-surfaces thereon and of the antifriction devices that are least exposed to wear to take the position of excessively-worn portions, substantially as described.
- 40 10. In a disk plow, the plow standard or hanger, and the bearing-plate adjustably secured thereto by a suitable fastening-bolt, and recesses on one of said parts to receive an interlocking lug or lugs on the other part, whereby the bearing-plate may be rotated about the fastening-bolt and secured in different positions; in combination with a composite antifriction-bearing for the rotary disk,

comprising a series of antifriction devices interposed between the back of the disk and a confronting bearing-surface on said bearing-plate, and an annular series of antifriction devices interposed between confronting bearing-surfaces on the opposite side of said support and a rotary element carried by or revolving with the disk, substantially as described.

11. In a disk plow, the plow standard or hanger, and the bearing-plate adjustably secured thereto by a suitable fastening-bolt, and recesses on one of said parts to receive an interlocking lug or lugs on the other part, whereby the bearing-plate may be rotated about the fastening-bolt and secured in different positions; in combination with a composite antifriction-bearing for the rotary disk, comprising a series of antifriction devices interposed between the back of the disk and a confronting bearing-surface on said bearing-plate, and an annular series of antifriction devices interposed between confronting bearing-surfaces on the opposite side of said support and a rotary element carried by or revolving with the disk; and flat rings apertured at intervals to receive and hold said antifriction devices at suitable distances apart in their respective races, substantially as described.

12. In combination with the rotary disk, and an annular series of antifriction devices, such as balls or rollers, a flat spacing-ring having a series of apertures therein to receive and hold said antifriction devices apart in rotary contact with opposing bearing-surfaces between which the antifriction devices are confined, and protuberances thereon for holding the spacing-ring between confronting surfaces in alinement with the centers of the antifriction devices, substantially as described.

13. The combination with the rotary cutting-disk, of a relatively-fixed part or sup-

port to which the disk is rotatably secured, a series of rollers interposed between confronting bearing-surfaces on said fixed part and the back of the disk, at a point between the center and circumference of the disk considerably removed from its center, and a similarly-arranged series of balls interposed between confronting bearing-surfaces on the opposite side of said fixed part and a member carried by or revolving with the disk, substantially as described.

14. The combination with a rotary cutting-disk, of a relatively-fixed part or support to which the disk is rotatably secured, a series of conical rollers interposed between the back of the disk and a confronting bearing-surface on said support at a point between the center and circumference of the disk, and a series of balls interposed between confronting bearing-surfaces on the opposite side of said support and an element carried by or revolving with the disk, substantially as described.

15. The combination with a rotary cutting-disk, of a relatively-fixed part or support to which the disk is rotatably secured, an annular series of rollers interposed between the back of the disk and a confronting bearing-surface on said fixed part at a point between the center and circumference of the disk, a series of balls interposed between confronting bearing-surfaces on the opposite side of said support and a member carried by or revolving with the disk, and means for loosely confining said rollers and balls at prescribed distances apart between said bearing-surfaces, substantially as described.

In testimony whereof I affix my signature in presence of two witnesses.

STALEY D. POOLE.
